UNITED STATES PATENT OFFICE.

MARGARET MAGUIRE, OF LONDON, ENGLAND.

BOOK CARRIER.

1,411,175.

Specification of Letters Patent. Patented Mar. 28, 1922.

Application filed May 25, 1921. Serial No. 472,406.

To all whom it may concern:

Be it known that I, MARGARET MAGUIRE, a subject of the King of England, residing in London, England, have invented certain new and useful Improvements in Book Carriers, of which the following is a specification.

This invention is for improvements in or relating to book or like carriers and has for its object to provide a simple device which can be readily attached to a book or like article and by which the latter can be conveniently carried. For convenience the term "book" will be employed herein to denote also other like articles, such for example as a portfolio or carrier for loose documents and where the term "book" occurs it is to be understood to include all such articles.

According to the present invention a carrier comprises a flexible band which is combined with clips for detachably securing it to the free edges respectively of the front and back covers of the book, is of such length as to pass round the back of the book from clip to clip and to leave one end portion extending clear of and beyond one of the clips, and has means detachably to secure the said end portion to the opposite end of the band or to the other clip with a part of the said end portion remaining free to serve as a handle.

Conveniently the said end portion, which serves as a handle, is in the form of a loop and in a preferred form of the invention both end portions of the band extend clear of the clips and a ring or the like is provided on one portion through which ring the other end portion, for example the looped end portion, may be passed.

The purpose of such a construction is that, by passing, for example the looped end portion through the ring, the book is held closed and a loop is afforded which can be slipped for example over the arm or held comfortably in the hand of the user.

A further feature of the invention consists in the provision of means combined with at least one of the clips whereby the latter may be secured to the band in any desired position of adjustment in the length thereof. This affords a means for adjusting one and the same carrier to different sizes of books.

The invention will be more clearly understood from the following description given by way of example only in connection with

the accompanying drawings which illustrate several embodiments of the invention and in which—

Figure 1 shows the book-carrier removed 60 from the book;

Figure 2 shows the carrier applied to the cover of the book with the book open;

Figure 3 shows the carrier applied to the book with the book closed; 65

Figure 4 illustrates a modified form of carrier applied to larger articles such as portfolios;

Figure 5 illustrates a modified form of book-marker to be employed with the carrier; and 70

Figure 6 shows a carrier, similar to, but slightly modified from, that illustrated in Figure 1.

Like reference numerals indicate like 75 parts in the several figures of the drawings.

Referring first to Figures 1 to 4, two clips 1 and 2 are each formed from a plate of springy material bent back upon itself so as to clip over the free edges of a book-cover as shown in Figures 2, 3 and 4, the springiness of the clips enabling them to grip the edges of the book. Two parallel slots 3 and 4 are cut close to one another from that portion of the clip 1 which will 80 lie over the outer surface of the cover of the book. The portion of metal 5 between the slots is preferably slightly raised so that the flexible band 6 can be passed through the slots, in the manner clearly illustrated in Figure 1, under the raised strip 5. 85

The portion of the other clip 2 which will lie over the outer surface of the book-cover is combined with a gripping-device 7 similar, 90

for example, to those employed in gentlemen's braces and other articles of apparel so as to grip and firmly secure the clip 2 to the band in any desired position of adjustment in the length of the band. 95

The band 6 is formed of flexible material, preferably woven material or thin leather, such as webbing or other fabric of suitable length and at one end is formed into a loop 8. The size of the loop is preferably such 100 that it will readily pass over the hand of the user. To the other end of the band is secured, for example by stitching, a metal D or ring 9.

In assembling the carrier the looped end 110 8 is first passed through the slots 3 and 4 in the clip 1, the material, where it is se-

cured to the D 9 serving to prevent the other end of the band being pulled through the slot 3. Alternatively other means may be employed to provide a stop to prevent the 5 band being pulled through the slot, for example a thickening of the material of the band at any desired position. The looped end 8 is then passed between the gripping-device 7 and the clip 2 and the carrier is 10 then complete.

In use the two clips are passed over the free forward edges of the front and back covers of the book as shown in Figures 2 and 3, and the length of the band is adjusted by means of the gripping-device 7 so that when the book is closed the band 6 will extend from clip to clip round the back of the book and will lie flat against the surface over which it passes and will be comparatively taut. This is shown clearly in 15 Figure 3. With the band so applied the book can be opened freely for reading and when it is desired to carry the book the latter is closed and the looped end 8 of the band is passed through the D or ring 9, thus holding the book closed as in Figure 3, with the looped end of the band projecting beyond the D or ring 9 to serve as a handle by which the book can be carried.

Conveniently the D or ring 9 is sewn in 20 a bight of the band, leaving a free end portion 10 which can be utilized as a book-marker to be inserted between the leaves of the book before it is closed as shown in 25 Figure 3.

An alternative form of book-mark is illustrated in Figure 5 in which the part 10 is dispensed with and in its place a light cord or string 11 is secured at one of its ends 30 to the end of the band 6 in the region of the D or ring 9, and at its other end to a clip 12 which is capable of clipping on to the top edge of the book. Thus the cord 11 will lie across the corner of that page of 35 the book at which it is desired it shall open, as will be readily understood.

In Figure 4 a modified form of carrier has been shown as applied to a portfolio. The band 6 and its clips 1 and 2, gripping-device 7 and ring 9, are formed as before but 40 within the loop 8 is a stiffener of wood, cane, metal or other preferred material to retain the central portion 13 in a flat or extended condition and to afford a more comfortable 45 handle. Combined with the band 6 is another flexible strip 14 which may be slidably engaged with the band 6 by means of a loop of material 15. A securing- or gripping-device 16, or alternatively a buckle, 50 may be employed for fastening the free end of the strip 14. The purpose of the band 14 is to give extra security in holding the portfolio closed. Such a carrier could also 55 be used with books if desired.

In Figure 6 a slightly modified form of 60 carrier is shown. Instead of securing the D or ring 9 to the band 6 by stitching, it is secured in a loop or bight of the band 6 with the aid of another smaller ring 19 which, as shown, gathers the band tightly round the 70 D or ring 9 and holds it in place. This form is particularly suitable when the band 6 is made of woven or like material but if leather be employed as the material of the band, stitching as in Figure 1 is preferable. 75 The spring clips 1 and 2, instead of having a plane gripping-surface, are shouldered as at 21 and 22. This is found to facilitate the application of the clips to the covers of the book and to ensure a firm grip. Further, 80 such a clip accommodates itself more quickly to covers of different thicknesses.

It will be appreciated that many modifications may be made in the details of construction without departing from the spirit of 85 the invention. For example it is not essential that the end portion serving as a handle should be formed as a loop although, as will be readily understood, it is desirable that it should be so formed to provide a convenient form of handle. Instead of providing the ring 9 on the end of the band it could be provided on the clip connected with that end.

By making the band completely detachable from the clips as hereinbefore described, 90 the same clips can be used with different bands, for example bands of different colours or different material, and the band itself may be formed with decoration in the way of 100 embroidery or the like as may be found desirable.

The clips are preferably made of metal 105 and may be themselves covered, for example with leather or other material to enhance their appearance.

In a modified form either or both of the clips may be such that the portion overlying the outer surface of the cover is sufficiently long to extend almost from the outer edge 110 of the cover to the back and would be formed with another pair of parallel slots near its other extremity. Or it may be of less length but similarly formed with two pairs of parallel slots. In either case the band is 115 passed underneath both of the strips separating the pairs of slots and is thereby maintained more closely to the covers when the book is opened.

As a further modification the clip 1 may 120 be rigidly secured to the band, for example by rivetting.

What I claim as my invention and desire to secure by Letters Patent is:—

1. A book-carrier comprising in combination, a flexible band, clips for detachably securing the band to the free edges respectively of the front and back covers of the

- book, said band being of such length as to pass round the back of the book from clip to clip and to leave one end portion extending free beyond one of the clips, and means 5 operatively connecting in a detachable manner said free end portion to a part of the carrier in the region of the opposite end of the band with a part of said free end portion available to serve as a handle.
- 10 2. A book-carrier according to claim 1 wherein the said free end portion which serves as a handle is formed with a loop, substantially as described.
3. A book-carrier according to claim 1 15 having both end portions of the band extending clear of the clips, and a ring or the like on one portion through which ring the other end portion may be passed, for the purpose described.
- 20 4. A book-carrier according to claim 1 having means combined with at least one of the clips whereby the clip may be secured to the band in any desired position of adjust-
ment in the length of the band, for the purpose described.
5. A book-carrier according to claim 1 wherein the clips are of such form that the band may be detachably secured to them.
6. A book-carrier comprising the combination of a flexible band having a loop at one 30 end and a ring or **D** at its other end, two clips to engage the book-covers, one of which clips has a gripping-device by which it can be adjusted in its position along the length of the band, and a book-marking 35 device.
7. A book-carrier according to claim 1 combined for the purpose described with a second flexible band adjustably secured to the flexible band of the book-carrier and 40 arranged transversely of the latter, and means to secure the ends of the said second band.

In testimony whereof I affix my signature.

MARGARET MAGUIRE.
